UNITED STATES PATENT OFFICE.

CORNELIS BOL, OF EINDHOVEN, NETHERLANDS, ASSIGNOR TO GENERAL ELECTRIC COMPANY, A CORPORATION OF NEW YORK.

SEALING-OFF MACHINE.

Application filed February 14, 1924, Serial No. 692,853, and in Holland March 19, 1923.

This invention relates to apparatus for sealing off a number of parallel glass tubes and more particularly the exhaust tubes of bulbs for electric lamps and other vessels to be exhausted, after said bulbs have been exhausted and provided, if necessary, with a suitable gaseous filling.

The apparatus according to the invention comprises a frame which is reciprocatable in the direction of the axis of the tubes so that the tubes are carried along by the frame in one direction, the said frame having attached thereto a burner for each tube. The said apparatus is preferably so designed that gas can be supplied to the burners during the reciprocating movement of the frame.

Each burner is preferably so arranged that it directs several radial flames on to the circumference of the glass tube.

If the invention is to be applied to simultaneously sealing off a number of exhaust tubes of bulbs for electric lamps or other hollow vessels to be exhausted, a vertically reciprocatable table may, according to the invention, be provided having attached thereto a burner for each exhaust tube and having apertures to receive the said exhaust tubes so that as the said table moves upwards after the sealing-off operation, the bulbs alone are carried along and the exhaust tubes remain behind.

If the burners are to be used also during the reciprocating movement of the table, gas may be supplied to the burners through a hollow shaft or hollow shafts to which the frame is attached.

The apparatus according to the invention for simultaneously sealing off a number of exhaust tubes can be applied to various known pump installations. It can be used for sealing off vacuum lamps as well as gas-filled lamps.

The bulbs to be exhausted are connected to the vacuum conduit by the exhaust tubes which may in known manner be fused to glass tubes, communicating with the vacuum conduit or which may also in known manner, be placed in tubes of elastic material such as rubber which tightly surround the exhaust tubes.

The advantages of the invention are enhanced by the use of special devices for holding and making a temporary hermetic seal around the exhaust tubes. The said devices are hereinafter referred to as locking de-

vices and comprise a tubular body of elastic material, devices for clamping both ends thereof and a device for pressing the free middle part of the elastic body against the wall of the exhaust tube by means of a liquid or a gaseous medium under pressure. In this case said locking devices are located below the apertures in the vertically reciprocatable table in which the exhaust tubes of the bulbs are inserted.

The advantages offered by such an arrangement are very considerable as the exhaust tubes can be placed in the locking devices without any difficulty so that it is possible to insert a number of lamps in the pump installation within a very short time, whilst also the sealing-off operation subsequent to exhaust can be carried on very quickly by using the device according to the invention.

The accompanying drawing illustrates by way of example a pump installation embodying the invention.

Figure 1 is a front view of the installation and Figure 2 is a vertical cross-section with a partial side view of the installation as shown in Figure 1.

As shown in the drawing, various parts of the device are secured to two plates 1 and 17 resting on legs 18 and 19. The plates 1 and 17 have fastened thereto an angle-iron 2 which supports bent hangers 3 and 43 on which are placed the locking devices which will be described hereinafter.

Two vertical shafts 4 and 5 are slidable vertically in brackets 6, 7 and 8, 9 which are attached respectively to the plates 1 and 17. The said vertical shafts carry the sealing-off device which will be described in detail hereinafter.

Each shaft 4 and 5 is provided with a toothed rack 10 which engages a toothed wheel 11 keyed to a horizontal shaft 12 which is rotatably supported in the plates 1 and 17 and carries a hand wheel 13 rigidly mounted thereon. By operating the hand wheel 13 a sealing-off cap 20 can be raised or lowered relatively to the locking devices. A counterweight 15 which is attached to the hand wheel 13 by means of a belt 14 secured thereto by a stud 16 insures that the locking device remains stationary in any position to which it has been raised or lowered.

The hangers 3 and 43 support vacuum conduits 21 and 22 which are closed at both

ends and connected by a tube 23. The conduits 21 and 22 carry a number of vertical tubes 24 and 25 at the ends of which are disposed the locking devices 26 and 27 which 5 serve to make a temporary hermetic seal around the exhaust tubes.

In the apparatus illustrated there are six 10 vertical tubes for each vacuum conduit. It will be clear, however, that a greater or smaller number of vertical tubes can be used, if desired.

One of the locking devices 26 will now be described in detail by reference to Figure 2. A tube 28 of elastic material such as 15 rubber is slid over the upper end of the tube 24 and is hermetically clamped at both ends. Its lower end is held between the lower end of a metal tube 29 and a conical portion of the tube 24 and its upper end is 20 bent around the upper end of the tube 29 to which it is clamped by a small metal cap which is drawn downward by springs 30 and 31 having their lower ends secured to a ring 32 rigidly attached to the tube 24. 25 A rod 35 of small diameter is vertically slidable in a small tube 34 within the tube 24. The said rod 35 which is resiliently supported by a coiled spring 33 is flattened at the upper end where it carries a small 30 ring 36 thus allowing an exhaust tube 42 to rest on it.

In order that the tube 28 shall not be heated to an objectionably high temperature some suitable cooling liquid such as water 35 is caused to circulate through a conduit 37 around the said metal cap.

As shown in Figure 1 said conduit is 40 led along all the locking devices. The cooling liquid is supplied from a tube 38 through a cock 39 and the conduit 37 is 45 opened out at the other end into two tubes 40 and 41 of small diameter thus allowing the water to flow into the enlarged upper end of an outlet tube 84, such end being for example of glass.

The middle portion of the tube 28 (Figure 2) can freely move relatively to the 50 wall of the metal tube 29 so that the tube 28 by the supply of a gaseous or a liquid medium under pressure can be hermetically pressed against the exhaust tube 42.

In order to cause the tube 28 to fall back 55 out of engagement with the exhaust tube 42 it is advisable to connect the space between the tube 28 and the metal tube 29 with a vacuum.

A conduit 45 extends at one end through the wall of the tube 29 and is at the other 60 end connected to a horizontal tube 47 which is secured to a support 48.

The locking devices 27 are connected to the tube 47 in a similar way by conduits 46. From the tube 47 is led downward a 65 tube 49 which communicates with a three-way cock 50. The latter connects the tube

49 either with a conduit 51 for air under pressure or with a preliminary vacuum conduit 53 and thus by turning the cock 50 the space around the elastic tube 28 can be connected alternately with a vacuum and 70 with air under pressure.

The horizontal vacuum tube 21 has connected thereto a tube 55 which by means of a cock 56 can be connected to a vacuum conduit 57.

The vacuum conduit 57 can be connected in known manner either to a preliminary vacuum or to a high vacuum. The apparatus may also be provided with a feed tube for some gas such as argon or nitrogen 80 with which the bulbs after exhaustion may be filled, if desired. It will be observed that not all of the aforesaid parts are shown in the drawing.

The sealing-off cap will now be described 85 in detail.

The vertical shafts 4 and 5 carry at their upper end the two cross beams 20 and 44 respectively (Figure 1) to which plates 64 and 65 (Figure 1) and a table 62 are secured by bolts 60 and 61 (Figure 2). The space between the plates 64 and 65 is filled with a heat insulating material 66 such as asbestos so that the locking devices 26 and 27 are protected against high temperature 90 when in the vicinity of the burners. A number of apertures 67 and 68 in the plates 64 and 65 corresponding to the number of locking devices allow for the passage of the exhaust tubes. Opposite the said apertures are openings in the table 62 to hold the bulbs 63.

It may be observed that the exhaust tubes 42 and the bulbs 63 are shown in the drawing in the position which they occupy 100 after the bulbs have been exhausted and sealed off.

In the vicinity of each set of apertures, radial burners 69 and 70 for heating the exhaust tubes are disposed. A mixture of 110 gas and air is forced to said burners through tubes 71 and 72 which are supported on the plate 65 and are connected to channels 73 in the shafts 4 and 5.

At the lower end of said channels, tubes 79 and 75 respectively are slidably mounted. The hermetic enclosure between the shafts 4 and 5 and the conduits 75 and 79 is insured by stuffing boxes 74 and 76.

The tubes 79 and 75 are connected to a 120 tube 77 which in turn is connected with a shut-off cock 78 through which a mixture of gas and air can be supplied from an air tube 80 and a gas tube 81.

It may be observed that the locking devices 26 and 27 are disposed between protecting walls 82 and 83 provided with a heat insulating material.

In order to heat the bulbs during exhaustion any suitable known device may be em- 130

ployed. Such a device is not shown in the drawing as its construction does not fall within the scope of the invention.

The operation of the device according to 5 the invention as shown in the drawing will now be briefly described.

At the beginning of the operation the sealing-off cap is in its lowest position. The bulbs to be exhausted are then placed by 10 the operator with their exhaust tubes in the corresponding apertures of the sealing-off cap. In doing so the lower ends of the exhaust tubes are seated on the upper ends of the small rods 34 within the locking devices. 15 The weight of the bulbs slightly compresses the springs 33. By turning the cock 50 air under pressure is then forced into the locking devices so that a temporary hermetic seal is obtained around the exhaust tubes, 20 whereupon the exhaust operation can be started. To that end the cock 56 is placed in the open position so that the tubes 21 and 22 are connected to a vacuum tube 57. The latter may be first connected with a preliminary 25 vacuum and then with a high vacuum. During exhaustion the lamps are preferably heated to the maximum temperature allowable by means not shown on the drawings. If desired, the bulbs can be provided 30 with a suitable gaseous filling. When a sufficiently high vacuum is obtained or when the bulbs are filled with the desired gas the gas cock is opened and the gas flames near the burners 69 and 70 are ignited. The 35 glass of the exhaust tubes is thereby softened near the bottom of the bulbs and thus the exhaust tubes are sealed off. When the operator sees that the sealing-off operation has sufficiently proceeded he raises the sealing- 40 off cap, the exhaust tubes being thus left in the locking devices. By that time the cock 56 is closed and at the same time the cock

50 is turned to the position in which the locking devices are connected with the preliminary vacuum so that the walls of the 45 elastic tubes 28 fall back out of engagement with the exhaust tubes. Thereupon the exhaust tubes can freely move in the locking devices and are raised by the springs 33 which were compressed by the weight of the 50 bulbs thus allowing the easy removal of the exhaust tubes from the locking devices. The finished bulbs are withdrawn from the sealing-off cap and fresh bulbs inserted 55 whereupon the cycle of operations is repeated.

What I claim as new and desire to secure by Letters Patent of the United States, is:—

1. In a device of the character described, the combination of a plurality of exhaust 60 heads for holding exhaust tubes side by side, a table mounted to overhang said heads and to reciprocate along said tubes, said table being heat insulated to adapt it to form the 65 bottom of an oven and having openings through which said tubes may extend above the table, means on said table for fusing said tubes near the top of said table, and manually operable means for at will reciprocating said table.

2. In a device of the character described, the combination of a reciprocating heat insulated table having transverse slots, means for at will raising and lowering said table, 70 exhaust heads mounted underneath said table to register with the inner ends of said slots and constructed to hold exhaust tubes, and burners mounted on said table to direct flames across said slots at a point adjacent the top of said table.

In witness whereof I have hereunto set my hand this 23rd day of January, 1924.

CORNELIS BOL.
